J. W. COSGROVE,
SOLE FITTING MACHINE,
APPLICATION FILED OCT. 19, 1917.

1,375,676.

Patented Apr. 26, 1921.

Inventor,
John W. Cosgrove
by his attorney
Walter E. Tracy
& F. J. Oldfield

UNITED STATES PATENT OFFICE.

JOHN W. COSGROVE, OF MEDFORD, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-FITTING MACHINE.

1,375,676.

Specification of Letters Patent. Patented Apr. 26, 1921.

Application filed October 19, 1917. Serial No. 197,464.

To all whom it may concern:

Be it known that I, JOHN W. COSGROVE, a citizen of the United States, residing at Medford, in the county of Middlesex and 5 State of Massachusetts, have invented certain new and useful Improvements in Sole-Fitting Machines; and I do hereby declare the following to be a full, clear, and exact 10 description of the invention, such as will enable others skilled in the art to which it appertains to make and use the same.

This invention relates to sole fitting machines and more particularly to such machines for preparing the toes of insoles for 15 the lip turning operation, such as the machine illustrated and described in Letters Patent of the United States, No. 1,087,578, dated February 17, 1914, to John B. Hadaway.

20 The present invention relates to improvements in the sole engaging devices for fitting machines adapted particularly to the mechanism of the machine of said patent, although those skilled in the art will recognize that 25 the scope of the invention is not limited to sole fitting machines for performing the special operation therein described.

The objects of the invention will be apparent from the following description of 30 the features and combinations of parts by which the objects are attained, and which are illustrated in the accompanying drawings of the preferred form of the invention.

In the drawings Figure 1 is a front elevation of the head of the machine shown in said patent, with the present improvement 35 added; Fig. 2 is a central, vertical section through the head shown in Fig. 1; Fig. 3 is a plan of the improved work support; and

40 Fig. 4 is a detail of parts to be described.

In the embodiment of the invention illustrated in the drawings the frame 5 of the head, the reciprocating plunger 7 carrying the V-shaped lip knife 9 and the incising 45 flap knife 11, driven by the wrist pin 13 on the driving shaft 15, and the work supporting table 17 carried on the yielding plunger 19 guided in the lower part of the frame 5; all may be, and preferably are, of the same 50 design as like parts in said patent. The operating mechanism for the driving shaft 15 may be of any convenient design but is preferably constructed like that illustrated in said patent wherein the revolutions of

the shaft are controlled by a one revolution 55 clutch of the Horton type operated by a foot treadle, all as usual and well known.

In the machine of said patent two presser gages are provided, one at each side of the knives 9 and 11 carried at the lower end of 60 a presser bar 21 mounted for vertical adjustment on the knife plunger 7. It has been found that in the machine of said patent there is a decided tendency for the sole to "pick up" or rise with the knives embedded 65 therein, which undesired movement is objectionable in that in removing the sole from the knives, which is done hastily, either the flap knife is broken or the sole is mutilated by tearing out the knives, especially when 70 the cuts are made before the sole is channeled. In the present improved construction this objection is overcome by counterboring the two depending feet 23 and 25, which formed the old presser gages, and 75 setting in the bores spring pressed plungers having flat heads 27. (Figs. 1 and 3). The construction is clearly understood from the sectional view shown in Fig. 4 in which view the springs 29, which normally maintain the 80 heads 27 advanced as shown in Figs. 1 and 2, are compressed by contact with the sole being operated upon. When the plunger 7 moves in a direction to carry the presser bar 21 upward the pressure on the heads 27 85 from their springs 29 causes them to hold the sole on the work table and act as strippers permitting the knives to be withdrawn from the sole. It will be noted that the stripper 90 heads 27 also perform the function of gag- 90 ing the depth of cut of the knives when the springs 29 are under compression, as in Fig. 4.

In addition to the improvement just described the invention embodies improved 95 means for positioning a sole on the work table. In the machine of said patent sole gages were provided which required adjustment for each new size or style of sole to be operated upon. As designed by the present 100 invention the sole gages automatically accommodate themselves to all sizes and styles, at the same time permitting free operation of the sole stripping devices just described. The desired construction is provided by an 105 improved mounting of the two side gages 31 which coöperate, in positioning a sole beneath the knives, in the usual manner with

the adjustable toe gage 33 found in the machine of said patent. The side gages 31 comprise suitably shaped sole engaging ends (see Figs. 1 and 2) on arms 35, extending 5 outwardly across the top of the work table, having their outer ends clamped, by rigid tongue and groove connections, one to each of the outer ends of two levers 37, extending inwardly beneath the table, and ful- 10 crumed on separate pivots 39 formed by screws threaded into the under side of the table. The levers 39 are connected by inter- meshing gear segments 41 on the hubs at their inner ends, and a spring 43 is connected between one segment and the table 15 so as to normally maintain the gages 31 in a position of approach. With this arrangement, on placing a sole in the machine the gages are forced apart and are held yield- 20 ingly to the sole whatever its toe contour may be. A lug 45 on one of the segments 41 engages an adjustable stop 47, carried below the work table, to limit the approach movement of the gages. It will be noted that the 25 side gages 31 have built up walls 49 at their sole engaging sides, of a sufficient length and height to insure an engagement with the sole edge should the sole be warped or bent so as to throw the forepart upward as fre- 30 quently occurs. Furthermore the design of the arms 35, carrying the gages, is such that even when in their position of closest approach the presser gages and strippers 27 are always able, on descending, to engage 35 the face of the sole, no matter how far the strippers may project beyond the edges of extremely pointed toes.

In operating the machine the relative position of the gages is such that the toe of the sole is correctly positioned, and is held, for the cuts to be made by the knives, whatever the contour of the toe may be, and after the power is applied the cuts are made cleanly and accurately due to the combined action 40 of the strippers and gages, all without injury to the knives.

The nature and scope of the present invention having been indicated and the preferred embodiment of the invention having 50 been specifically described, what is claimed as new, is:—

1. A sole fitting machine, having, in combination, a knife for cutting into the marginal portion of a sole, gages for engaging 55 the edge of the sole to position it for the operation of the knife, and a combined presser gage and sole stripper adjacent the knife.

2. A sole fitting machine, having, in com- 60 bination, a knife for cutting into the marginal portion of a sole, and a combined presser gage and sole stripper at each side of the knife.

3. A sole fitting machine, having, in com- 65 bination, a knife for cutting into the mar-

ginal portion of a sole, gages for engaging the edge of the sole at each side of the knife to position the sole for the operation of the knife, and a combined presser gage and sole stripper between each gage and the knife. 70

4. A sole fitting machine having, in combination, a yielding work table, a positively reciprocated knife arranged to incise a sole on the table, and a depth gage comprising a plunger having a limited yielding move- 75 ment movable with the knife.

5. A sole fitting machine, having, in combination, a work table, a toe cutting tool, a sole stripper at each side of the tool which may project beyond the sole edge, and a 80 pair of side gages yieldingly held in their position of nearest approach to the tool, constructed and arranged to clear said strippers when in such position.

6. A sole fitting machine, having, in combination, a work table, a tool, means for positioning a sole for the operation of said tool comprising a toe gage and side gages carried on arms having hubs fulcrumed on independent pivots beneath the table, said 90 hubs having inter-meshing gear segments whereby the gages are moved in unison, and a suitably connected spring for holding the side gages yieldingly inward toward the toe gage. 95

7. A sole fitting machine, having, in combination, a work table, a tool above the table, a toe gage, and side gages co-operating therewith comprising arms extending across the upper side of the table having gaging 100 ends adjacent each side of the toe gage, supports for said arms extending across the lower side of the table, pivots for said supports beneath the table, and means for yield- 105 ingly, articulately connecting said supports beneath the table.

8. An insole fitting machine, having, in combination, a work table, two knives above the table for cutting the material of the lip and the flap at the point of the toe of the 110 insole, a toe gage, yielding side gages extending inwardly across the table toward the toe gage adapted to open as an insole is thrust between them, and a sole stripper at each side of said knives. 115

9. A sole fitting machine having, in combination, a yielding work table, a positively reciprocated knife arranged to incise a sole on the table, and a combined presser gage and stripper movable with the knife con- 120 structed and arranged to yieldingly engage the sole in advance of the knife, then to form an unyielding abutment to gage the depth of the incision and finally to strip the sole from the knife.

10. A sole fitting machine having, in combination, a work table, means for positioning a sole thereon comprising side gages movable in a plane above and parallel to the top of the table and carried on members 130

having hubs fulcrumed on independent pivots beneath the table, said hubs having intermeshing gear segments whereby the gages are moved in unison, and means for 5 yieldingly pressing the gages toward each other.

11. A sole fitting machine having, in combination, a work table, a tool, and means for positioning an end portion of a sole for the 10 operation of said tool comprising edge gages

movable in a plane above and parallel to the top of the table into contact with the sole near its end and carried on members fulcrumed on independent pivots in front of the tool and edge gages, connections for 15 causing the gages to be moved in unison and means for yieldingly pressing the gages toward each other.

JOHN W. COSGROVE.
